UNITED STATES PATENT OFFICE.

JAMES A. BOALS, OF BURGETTSTOWN, PENNSYLVANIA, ASSIGNOR TO W. P. VANCE AND ALEXANDER MCCLINTOCK, BOTH OF SAME PLACE.

CHURN-POWER.

SPECIFICATION forming part of Letters Patent No. 296,512, dated April 8, 1884.

Application filed November 15, 1883. (No model.)

To all whom it may concern:

Be it known that I, JAMES A. BOALS, a citizen of the United States, and a resident of Burgettstown, in the county of Washington and State of Pennsylvania, have invented certain new and useful Improvements in Churn-Powers; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my improved churn-motor; and Fig. 2 is a side elevation of the motor mechanism, one of the sides of the frame having been removed.

Similar letters of reference indicate corresponding parts in both the figures.

My invention has relation to mechanical powers for operating churning of that class which are actuated by a spring or weight; and it consists in the construction and combination of parts of the same, which will be hereinafter more fully described and claimed.

In the accompanying drawings, A is the frame or casing which contains the operating mechanism. B is the main shaft, which is boxed in the sides of the frame. C is the actuating-spring, and D is the main wheel. Instead of the spring C, which is wound by a key or crank placed upon the squared outer end of the main shaft B, I may use one or more weights with cords wound around drums or pulleys upon the main shaft, if desired; or a clock mechanism of any desired construction may be used for rotating the main shaft B and drive-wheel D. The latter gears with a pinion, E, fixed upon a shaft, F, in the top part of the frame. Upon the shaft F is also keyed the star-wheel G, which, in the present illustration of my invention, has six radial arms or spokes, g. H is another shaft, which is fixed in a frame, and upon which is hung a bifurcated lever composed of the two arms I and J, the upper arm, I, having a box, i, through which shaft H is inserted. This arm also has a pin or stud, K, for the attachment of one end of a spring, L, the other end of

which is fastened in an eyebolt, M, inserted through the cross-piece N of the frame, in which it may be adjusted, so as to regulate the tension of the spring, by means of a nut, O, or equivalent means. The lower arm of

the bifurcated lever is bent, as shown in the drawings, and provided at its free end with a friction-roller, P. To the outer end of the lever is attached the staff Q of the reciprocating dasher, which works in the churn R, and which said dasher may be of any desired construction suited for the purpose.

From the foregoing description, taken in connection with the drawings, the operation of my motor will readily be understood without requiring extended explanation. It will be seen that as the star-wheel G revolves in the direction of the arrow its arms will strike the under side of the upper arm of the bifurcated lever, and thus tilt the same upon its shaft H. At the moment when arm g is released from the lever the friction-roller at the outer end of the curved arm J will be in such position as to bear against one of the other arms of the star-wheel, as illustrated in Fig. 2, and as the wheel revolves this arm, bearing against the roller, will force the bifurcated lever in a downward direction, and thereby bring its straight upper arm in the proper position for receiving the stroke of the arm g next in front of it. Thus it will be seen that there will be a short stop or intermission between each stroke of the lever, whereby I imitate the up-and-down motion of the dasher-staff, as this would be operated in churning by hand in the usual manner. The spring L serves the double purpose of cushioning the strokes of the lever and also of properly adjusting the bifurcated inner ends of the same, so as to be in the correct position for being actuated by the star-wheel in the manner described.

Having thus described my invention, I claim and desire to secure by Letters Patent of the United States—

In a mechanical motor for churning, the combination of the actuating mechanism, shaft F, having pinion E, star-wheel G, bifurcated lever I J, having box i, pin K, and friction-roller P, shaft H, and adjustable spring L, substantially as set forth.

In testimony that I claim the foregoing as my own I have hereunto affixed my signature in presence of two witnesses.

JAMES A. BOALS.
